(57) **CLAIM**

The ornamental design of the medical instrument cap, as shown and described.

DESCRIPTION

FIG. 1 is a side, exploded, perspective view of a medical instrument cap;

FIG. 2 is a back, exploded, plan view of the medical instrument cap of FIG. 1;

FIG. 3 is a front, exploded, plan view of the medical instrument cap of FIG. 1;

FIG. 4 is a right hand, exploded, plan view of the medical instrument cap of FIG. 1;

FIG. 5 is a left hand, exploded, plan view of the medical instrument cap of FIG. 1;

FIG. 6 is a top, plan view of the medical instrument cap of FIG. 1;

FIG. 7 is bottom, plan view of the medical instrument cap of FIG. 1;

FIG. 8 is a front, exploded, perspective view of an medical instrument cap;

FIG. 9 is a back, exploded, plan view of the medical instrument cap of FIG. 8;

FIG. 10 is a front, exploded, plan view of the medical instrument cap of FIG. 8;

FIG. 11 is a right hand, exploded, plan view of the medical instrument cap of FIG. 8;

FIG. 12 is a left hand, exploded, plan view of the medical instrument cap of FIG. 8;

FIG. 13 is a top, plan view of the medical instrument cap of FIG. 8;

FIG. 14 is bottom, plan view of the medical instrument cap of FIG. 8;

FIG. 15 is a side, perspective, assembled view of the medical instrument cap of FIG. 8.

FIG. 16 is a back, plan view of the medical instrument cap of FIG. 15;

FIG. 17 is a front, plan view of the medical instrument cap of FIG. 15;

FIG. 18 is a right hand, plan view of the medical instrument cap of FIG. 15;

FIG. 19 is a left hand, plan view of the medical instrument cap of FIG. 15;

FIG. 20 is a top, plan view of the medical instrument cap of FIG. 15; and,

FIG. 21 is a bottom, plan view of the medical instrument cap of FIG. 15.
